UNITED STATES PATENT OFFICE.

MARCUS O. ANTHONY, OF NEW YORK, N. Y., ASSIGNOR TO THE UNITED MACHINE & SUPPLY COMPANY, OF NEW YORK, N. Y., A CORPORATION OF NEW YORK.

COIN-CONTROLLED MECHANISM.

No. 844,909.

Specification of Letters Patent.

Patented Feb. 19, 1907.

Original application filed January 2, 1904, Serial No. 187,492. Divided and this application filed May 1, 1905. Serial No. 258,157.

To all whom it may concern:

Be it known that I, MARCUS O. ANTHONY, a citizen of the United States, and a resident of the city of New York, in the county of New York and State of New York, have invented certain new and useful Improvements 5 in Coin-Controlled Mechanism, of which the following is a specification.

This application is a division of an application 10 filed by me January 2, 1904, Serial No. 187,492, for improvements in vending-machines.

The subject of the present application relates to coin-controlled mechanism for use, 15 primarily, in connection with the said vending-machines, such mechanism combining simplicity and durability of construction with reliability and efficiency of operation and being hereinafter particularly set forth 20 and claimed.

In the drawings, Figures 1 and 2 are end and side elevations, respectively, of the coin-controlled clock mechanism and its adjuncts, showing the connections between such 25 mechanism and the discharge-pusher of the vending-machine. Fig. 3 is a similar side elevation with the coin-chute and part of the framework removed to expose the coin-actuated brake and trip devices.

14 designates the base-plate for the support of the clockwork mechanism 15. Guided in this plate is a cross-head 16, which is reciprocable through the instrumentality of the clock mechanism into and from the 20 lower part of a suitable article-containing magazine in a manner to eject from such magazine the lowermost article therein. The cross-head thus constitutes a pusher. It is connected on one side by means of a link 18 25 with the lower end of a lever 19, which is fulcrumed at its upper end to the frame of the clock mechanism, and is provided at a suitable point in its length with a cam-slotted portion 20, into which extends a wrist-pin on 30 a crank-disk 22, which is mounted on the end of a driven arbor 23 of the clock-movement, whereby during the operation of the latter the lever is oscillated to effect the reciproca- 35 tion of the pusher.

40 The mainspring 26 of the clock mechanism is wound up by a suitable key in the

usual way, and the parts are so arranged that the arbor 23 makes a single revolution each time the mechanism is set in operation by the dropping of a prescribed coin into the 55 machine, as follows: On an arbor 27, mounted in the frame and operatively geared with the clock - movement, is a brake-wheel 28, with which coacts a brake-shoe 29 on the upper end of a lever 30, which is pivoted at its 60 lower end to the clock-frame. The brake is maintained normally in engagement with the brake-wheel by the action of a suitable spring 31, so as to lock the clock mechanism. This lever is provided at its upper end with a 65 cam-head 32, against which bears the shorter arm 33 of a bell-crank lever, the longer arm 34 of which extends down near to the bed-plate 14 and is provided at its lower extremity with a coin-seat 35, having an upwardly 70 and rearwardly curving rear wall or extension 35^x. The coin-seat and its extension are normally swung by the action of the cam-head 32 of lever 30 on the arm 33 into the lower portion of a coin-chute 36, leading 75 from a coin-slot 37 in the top of the casing. Hence if a coin of predetermined denomination—that is, of a certain weight and diameter—be inserted in the slot it will descend to the bottom of the chute and abutting 80 peripherally against the coin-chute and the inclined extension will act with a cam-like action on the latter, and thus swing the same and the lever-arm 34 outwardly, thereby pressing the shorter arm 33 against the op- 85 posing cam-head 32 of the lever 30 and pushing the latter outward to effect the release of the brake, and thus permit the operation of the clock mechanism. Owing to the system of compound levers employed, comparatively 90 slight force at the coin-seat overcomes the action of the brake.

In order to permit a complete revolution of the arbor 23 on which the crank-disk 22 is mounted, there is affixed on said arbor a 95 cam 38, provided with an abrupt inward portion *a*, two concentric portions *b* *c*, and a projection *d*. The lever 30 is provided on its inner edge with a stud 39, which when the mechanism is at rest occupies the position 100 indicated in Fig. 3—that is, in engagement with the abrupt portion *a* of the cam. When

the brake is released, as above described, the cam is rotated in the direction indicated by the arrow in Fig. 3, its edge *b* turning in proximity to the stud of the brake-lever until the 5 cam has made about a half-revolution, (during which time the coin remains in its seat,) whereupon the cam projection *d* rides against the said stud 39 and forces the lever 30 farther outward to permit enough swing of 10 the lower end of the crank-lever to discharge the coin therefrom. The succeeding concentric portion *c* of the cam then engages the stud and prevents the swinging of the lever into braking action until the abrupt portion 15 of the cam escapes the stud, whereupon the parts resume their original or normal condition.

While I have herein shown and described a simple and efficient embodiment of my 20 invention, it is to be understood that the same may be modified in various respects without departing from the fair spirit of the invention. I therefore do not confine myself to the specific details of construction 25 hereinbefore set forth.

I claim—

1. In coin-operated mechanism, the combination of a brake device, a coin-receiving lever engaged therewith and adapted to release the said device upon the deposit of a 30 coin on said lever, and means independent of said lever for imparting an additional movement to the brake device after its release, whereby such movement is transmitted by the brake device to the coin-receiving lever to discharge the coin from the latter.

2. In coin-operated mechanism, the combination of a brake device, a coin-receiving 40 lever engaged therewith and adapted to release the said device upon the deposit of a coin on said lever, a cam engaging the said brake device, and means for operating said cam whereby an additional movement is imparted to the brake device after its release and such movement thus transmitted by the brake device to the coin-receiving lever to discharge the coin from the latter.

3. In coin-operated mechanism, the combination of locking devices, including a 50 brake-lever, a coin-receiving lever coacting with the brake-lever to release the latter upon the deposit of a coin on the coin-receiving lever, and means independent of the 55 coin-receiving lever for imparting additional movement to the brake-lever after its release, whereby such movement is transmitted by the brake-lever to the coin-receiving lever to discharge the coin from the latter.

4. In coin-operated mechanism, the combination of locking devices, including a brake-lever, a coin-receiving lever coacting with the 60 brake-lever to release the latter upon the de-

posit of a coin upon the coin-receiving lever, 65 a cam engaging the brake-lever, and means for operating said cam whereby an additional movement is imparted to the brake-lever after its release and such movement thus transmitted by the brake-lever to the coin-receiving lever to discharge the coin from the latter. 70

5. In coin-operated mechanism, the combination with a coin-guide, of a coin-receiving lever provided with a coin-seat adjacent 75 said guide, said seat being provided with an inclined extension against which and the wall of the guide the coin bears on its way to the seat proper.

6. In coin-operated mechanism, the combination of locking devices including a brake-lever, a coin-guide, a coin-receiving lever coacting with said brake-lever, said coin-receiving lever being provided with an inclined portion against which and the wall of the 85 guide the coin bears while descending said guide.

7. In coin-operated mechanism, the combination of locking devices including a brake-lever, a coin-guide, and a coin-receiving 90 lever coacting with said brake-lever, said coin-receiving lever having a coin-seat adjacent said guide and said seat having an inclined extension against which and the wall of the 95 guide the coin bears on its way to the seat proper.

8. In coin-operated mechanism, the combination of locking devices, a coin-guide, a coin-receiving lever coacting with said devices, said lever having a coin-seat adjacent 100 said guide, and said seat having an inclined extension against which and the wall of the guide the coin bears on its way to the seat proper, and means for imparting a supplemental movement to the said lever. 105

9. The combination with clock mechanism, of a brake member coacting therewith, a cam on an arbor of said mechanism, a brake-lever engaging said member and cam, a coin-receiving lever operatively engaged with the 110 brake-lever and provided with a coin-seat having an inclined extension and a coin-chute leading to said seat in such position that a coin introduced to the chute will engage the inclined extension and the opposing 115 wall of the chute.

10. The combination with clock mechanism, of a brake member coacting therewith, a cam on an arbor of said mechanism, a brake-lever engaging said member and cam, and a 120 crank-lever, the shorter arm of which engages said brake-lever, and the longer arm of which is provided with a coin-seat.

11. The combination with clock mechanism, of a brake member coacting therewith, a 125 cam on an arbor of said mechanism, a brake-lever engaging said member and cam, a crank-lever, the shorter arm of which en-

gages said brake-lever and the longer arm of which is provided with a coin-seat having an inclined extension, and a coin-guide leading to said seat in such position that a coin introduced to the guide will engage the inclined extension and the opposing wall of the chute.

5 Signed at the city of New York, in the

county of New York and State of New York,
this 11th day of April, A. D. 1905.

MARCUS O. ANTHONY.
